FIG. 23.

UNITED STATES PATENT OFFICE.

LEON J. LE PONTOIS, OF CLEVELAND, OHIO, ASSIGNOR, BY MESNE ASSIGNMENTS, TO THE TEAGLE COMPANY, OF CLEVELAND, OHIO, A CORPORATION OF OHIO.

APPARATUS FOR GENERATING HIGH-TENSION ELECTRICAL IMPULSES AND IGNITION SYSTEMS.

1,238,533.

Specification of Letters Patent. Patented Aug. 28, 1917.

Application filed January 21, 1913. Serial No. 743,358.

To all whom it may concern:

Be it known that I, LEON J. LE PONTOIS, a citizen of the Republic of France, residing at Cleveland, in the county of Cuyahoga and State of Ohio, have invented certain new and useful Improvements in and Relating to Apparatus for Generating High-Tension Electrical Impulses and Ignition Systems, of which the following is a specification.

This invention relates to apparatus for generating high tension electrical impulses and to an ignition system.

An object of my invention has been to provide a method of generating intermittent electrical impulses of high tension current for ignition purposes which could largely be effected in a single, extremely compact generating unit of high efficiency, simple and cheap construction, and great durability.

An object of my invention has been to produce an inductor alternator unit for generating intermittent electrical impulses of high tension current, in which the hysteretic and eddy current losses would be confined to a minimum, and in which the length of the iron circuit subject to magnetic flux variations would be as short as possible, in order that the number of lines of flux threading through the generating winding would be as great as possible at a given instant, and the magnetic flux threading through said winding should in the normal operation of the apparatus vary as much as possible.

I have also sought to maintain substantially a unidirectional flux through the flux distributing element or rotor and to maintain the reluctance of the magnetic circuit during the normal operation of the apparatus nearly constant.

Another object has been to accomplish the above desired results in an apparatus in which is employed permanent magnets and of so opening and closing the electrical circuit that the preponderating influence of the apparatus in its normal operation will be to maintain rather than to break down the permanent magnets.

It is well understood that for ignition purposes intermittent impulses of high tension current will suffice. My invention relates

especially to the generation and utilization of such impulse currents, as contra-distinguished from methods, systems or apparatus for constant current production.

Hereinafter I have undertaken to set forth and describe the method which I have invented as well as a system and apparatus, illustrative of my invention.

Figure 1 is a side elevation of an inductor alternator embodying my invention.

Fig. 2 is a vertical longitudinal section of the same, certain circuit completing parts being shown more or less diagrammatically.

Fig. 3 is a section on the line 3—3 of Fig. 2.

Fig. 4 is an end view of the apparatus.

Fig. 5 is a section on the line 5—5 of Fig. 2.

Fig. 6 is an end view of the field structure, the base being shown in transverse section, the coil being shown in position, the permanent magnets, however, being removed and also the rotor.

Fig. 7 is a side elevation of the center rib.

Fig. 8 is a top plan view of the same.

Fig. 9 is an end view of the said rib.

Fig. 10 is a perspective view of one of the spacing bars of non-magnetic material.

Fig. 11 is a side elevation of one of the magnet laminæ.

Fig. 12 is a side elevation of a modified form of magnet lamina.

Fig. 13 is an end view of the same.

Fig. 14 is a side elevation of one of the laminæ constituting the magnetic pole structure.

Fig. 15 is an end elevation of the same.

Fig. 16 is an end elevation of the automatic spark advance mechanism.

Fig. 17 is a view of the same with the end plate removed.

Fig. 18 is a section on the line 18—18, Fig. 17.

Fig. 19 is a perspective view of one of the centrifugal arms or weights.

Fig. 20 is a view corresponding with Fig. 3 excepting that the pole structure, base and rotor are shaped for generating three instead of two complete electrical cycles during one revolution of the rotor.

Fig. 21 is a view partly in side elevation

and partly in longitudinal section of a modified form of construction.

Fig. 22 is a rear end view of the generator shown in Fig. 21, the breaker casing end 5 plate being removed.

Fig. 23 is a section on the line 23—23 Fig. 21.

In the drawings:

- 1 indicates a casting comprising a section 10 or base 1^a, intended to rest upon a suitable support for the generator, a pair of annular pole pieces 1^b, 1^c, alined and spaced at opposite ends of the base section 1^a, and a centrally located pole piece 1^d having a polar 15 face 1^e. Whereas the parts referred to are illustrated and described as integrally formed it will be understood, that if desired, they may be separately formed and suitably assembled and held together. Each 20 of these pole pieces 1^b, 1^c in the illustrated embodiment of my invention has a horizontally disposed flat surface 2, arranged to magnetically contact with and support one polar end of a magnet structure to be 25 hereinafter described. Each of these annular alined pole pieces carries an upwardly extending, centrally disposed lug 2' to receive a bolt, the purpose of which will be later described.
- 30 3 are lugs, which may be formed integral with the base section, the purpose of which will be later set forth.
- 4, indicates a magnet structure, a preferred form consisting of a plurality of 35 laminæ 4^a of steel. In the construction illustrated in the drawing these laminæ are arranged in groups, on opposite sides of a center rib 5 of non-magnetic material. This center rib 5 has a horizontal section 5' at 40 its top, a centrally disposed inwardly extending projection 5^a, and at its opposite ends, arms 5^b, 5^c extending at an angle to the section 5'. The lower end of each arm 5^b, 5^c is recessed at 5^d to receive the adjacent lug 2' on the adjoining annular pole piece. 6 are bolts for securing the rib 5 to the lug 2'.
- Each of the magnet laminæ 4^a preferably 50 conforms in shape to the general shape of a half of the center rib 5, it having at the end of its outer or longer leg a polar surface 4^b arranged to make magnetic contact with the upper horizontal surface 2 of the adjacent pole piece 1^b or 1^c, as the case may be, and at the end of its inner or shorter leg a polar surface 4^c.
- There are four groups of laminæ shown 60 in the illustrated embodiment of my invention, two of which are arranged on one side of the rib 5 and the other two on the opposite side of that rib. The groups on the same side of the ribs have their shorter legs disposed adjacent to each other, so as to form consequent poles at this point of the field magnet structure. The magnet laminæ
- groups and the rib 5 may be firmly bound and held together in any suitable manner. For illustration I have shown this to be accomplished by means of rods or bars 7, passing through alined openings in adjoining parts, opposite ends of each stud or rod being upset against the adjacent wall of the adjoining part.
- 9 is a magnetic pole structure arranged to make magnetic contact on its upper edge 75 with the polar surfaces 4^c at the ends of the shorter legs of the magnet laminæ. This structure 9 is illustrated as composed of a plurality of laminæ 9^a of metal of high magnetic permeability and low reluctance, 80 as for example soft or annealed iron. Each of the laminæ has a horizontal section 9^b with polar projections 9^c at either end thereof and a centrally disposed and arranged polar projection 9^d. 9^e indicates the polar 85 faces of the extensions 9^c and 9^d the polar faces of the extension 9^d. 9^f are side plates of substantially corresponding shape to the soft iron laminæ 9^a. 10 are rivets, studs and screws by means of which the side 90 plates 9^e and laminæ 9^a may be suitably held or bound together.
- The lower ends of the longer legs of the side plates 9^e at the same ends of the structure 9 are connected together by means of 95 spacing bars 11, of non-magnetic material, and by means of screws or studs 11^a extending through such spacing bars into the adjacent ends of the side plates 9^e. Each of these spacing bars or plates 11 has a flange 100 11^b which registers with the adjacent lugs 3 on the base section 1^a. Dowel pins or screws 11^c extend between each pair of these lugs and the adjacent flange 11^b.
- 12 indicates as an entirety a rotor or flux 105 distributor constructed and disposed to cooperate with the polar surfaces of the annular pole pieces 1^b, 1^c and the polar faces 1^d, 9^e and 9^f to effect during its oscillation or rotation alternate paths of least magnetic reluctance, first between the pair of 110 polar faces 1^d and 9^f and then between the pair of polar faces 9^e. The illustrated embodiment of this rotor comprises a central and enlarged section 12^a having oppositely 115 disposed polar faces 12^b arranged to move in a path closely adjacent to the polar surfaces 1^d, 9^f and 9^e, 9^c. At either side of this central enlarged section 12^a the rotor is reduced in section and has cylindrical sections 12^c, 12^d, the former entering the annular pole section 1^b and the latter entering the polar section 1^c, the clearance between the annular polar surfaces and the corresponding cylindrical sections of the induc- 120 tor rotor being preferably as small as ordinary manufacturing facilities will permit, it being understood that the less the magnetic reluctance between these parts the better.

The front end of the rotor may be suitably formed or shaped to receive any well known kind of driving connection or coupling. The rear end of the rotor may be shaped and adapted to operate any suitable circuit opening and closing device, and distributor, or either of them.

The inductor rotor 12, near either end thereof, is mounted in suitable anti-friction 10 bearings 13 positioned within the annular pole pieces 1^b, 1^c. Nuts 14, 14, fitting screw threaded sections of the rotor serve to hold the said bearings 13 properly positioned. 15, 15', are end caps or plates detachably 15 secured to the base section 1 in such manner as to protect the bearings 14, 14, from dust or foreign matter and to properly position the bearings.

The inductor rotor just described may be 20 constructed in any suitable manner. It may be formed of one integral mass, may be laminated in whole or in part, or may be constructed as illustrated in the drawings wherein laminated sections 12^e are assembled between end plates 12', and bound together by rods or bars 12^e, upset at their ends, which laminated mass is forced into position on the rotor and made a part thereof by a suitable pressure.

30 16 is a generating coil. It is constructed so as to snugly fit over the polar projection 9^d. In the embodiment of my invention illustrated in the drawing the coil shown is ordinarily termed a coil for high 35 tension current induction. It has an inner section 16^a of relatively coarse wire and an outer section 16^b of relatively fine wire. It is to be understood that the apparatus may be easily adapted for what is ordinarily 40 termed low tension current generating purposes, merely by having a coil with but a single winding of relatively coarse wire. The coil 16 may be held upon the polar projection 9^d in any suitable manner.

45 17 is a terminal for one end of the coarse winding 16^a. This terminal is grounded by contact with the pole piece 9, which may be accomplished by a screw or in any other well known manner. At its other end the 50 coarse winding 16^a is connected to the inner end of the fine winding 16^b and also to a terminal lead 18. This terminal lead 18 is electrically connected to the inner end of a terminal piece 19 having at its outer end a 55 terminal post 20. The piece 19 and post 20 are insulated by material 21 from the centering rib 5, through which the piece 19 passes. This terminal piece 19 extends through and makes electrical contact with 60 a metal piece 22, which is electrically connected with and supports a metal box section 22'.

23 is a condenser electrically connected at one end to the terminal post 20 through 65 the shell section 22' and pieces 19 and 22.

The other end of the condenser is grounded by being electrically connected to a shell or box section 22' which is grounded to the frame and connected thereto by the screw 22'.

70

The fine winding 16^b at its periphery has a contact plate or button 24 in electrical contact with the end of the fine wire winding. 21' is a resilient conductor having at its free end a contact point 24^a normally held in engagement with the high tension terminal 24. 25 is an insulating plug having an enlarged section 25' and a tubular section 25^a, the latter passing through a suitable opening in the centering rib 5 provided therefor. 25^b is a nut for securing the insulating plug in position. 26 is a high tension terminal lead extending through the insulator 25 and connected at its inner end to a conducting plate 27 which is electrically connected at 28 to one end of the conductor 24'. 29 is a metal plate or button electrically connected to the pole piece 9 and suitably disposed relative to the connection 28 so as to form therebetween a suitable spark gap 30, this being a safety spark gap to preclude overstraining of the high tension circuit.

80

31 is a suitable binding post connection at the outer end of the terminal lead 26.

95

32 indicates as an entirety a suitable circuit opening and closing mechanism. This mechanism in the illustrated embodiment of my invention is disposed within the field structure. Of this mechanism 33 is an arm 100 pivotally connected at 34 to one section of a two part collar 35 arranged upon the inner end of the annular pole piece 1^b. 37 is a spring securely connected at 37' to a lug 35' on one section of said collar 35 and having its other end connected at 37^a to the heel of the breaker arm 33. At its free end the breaker arm 33 carries a movable breaker electrode 38 adapted to make electric contact with a normally stationary but adjustable breaker electrode 39, which is carried by a holder 40, suitably insulated from the collar 35 by the insulating material 41 and held in position thereon by a bolt 42, and screw 43, both suitably insulated from the 115 collar 35. Lateral movement of the collar 35 and breaker parts mounted thereon relative to the pole piece 1^b is prevented by forming an internal annular groove 35^b in the collar 35, which groove receives a 120 stud or studs 35^c carried by the pole piece 1^b.

44 is a hard fiber plug or shoe carried by the breaker arm 33 and arranged for engagement with the surface of a cam 45, mounted upon and rigidly secured to the 125 rotor 12, as by means of screws 45'.

The circuit is closed through the following conductors: low tension winding 16^a; lead 18; conductor 50 leading therefrom to bolt 42, thence through the holder 40, elec- 130

trodes 39 and 38, and breaker arm 33 to ground, the other terminal 17 of the coarse winding being grounded. The condenser 23 is disposed in the circuit across the electrodes 38 and 39, or in parallel therewith.

Purely for the purpose of illustration I have shown somewhat diagrammatically a high tension external circuit beginning at the binding post 31 and leading by conductor 51 to a spark gap or plug 52 and thence to ground.

It will be understood that to facilitate simplicity of the description, I have not shown any distributor mechanism for the purpose of distributing at predetermined intervals electrical impulses successively to a plurality of spark gaps or plugs. Any suitable and well known form of distributor can be readily applied to a generator embodying my invention, as will be readily understood by one skilled in the art.

There has been a demand for what is known as automatic spark advance in connection with electric generating devices for ignition purposes. In order to provide for such automatic spark advance I have invented a mechanism which in the drawings is indicated as an entirety as 80, it being arranged at the front end of the rotor shaft. Of this mechanism 81 indicates a gear rigidly secured to the rotor shaft and having hubs 81', 81''. Surrounding the said gear and loosely mounted at either side upon its hubs 81', 81'', is a casing 82, having journals 82', 82'' for said hubs. This casing comprises a cup shaped member 82^b and a cap or cover plate 82^c which are secured together in any suitable manner as by screws 82^a. The cover plate carries a forward extending clutch element 83 of any suitable design. 84 are centrifugally operated arms diametrically disposed within the cup shaped member 82^b, and each pivotally mounted near one end on a pivot pin 85, which pivot pin at one end is rigidly secured to casing member 82^b, while its other end is snugly fitted into a passageway provided for it in plate 82^c. Each of the arms 84 at its end nearest its point of pivotal connection with the casing 82, is provided with a gear segment 84' which meshes with the gear 81. 86 is a spring disposed in a recess in an arm 84 and bearing at its outer end against an element 86', carrying loosely an antifriction ball 86'' which rolls upon a wear plate 87 carried by the casing 82^b. The spring tends normally to press the free end of the arm 84 toward the axis of the rotor 12.

The method of generating electrical pulses and the operation of the generator will be readily understood.

Referring to Figs. 2, 3, and 4, if we consider 4^c as the polar face of the positive pole of the permanent magnet and 4^b as

the negative pole, we may take as the beginning of a cycle, the instant when the flux distributing section 12^a is in the vertical position and rotating counter-clockwise as indicated by the arrow. At this time the magnetic flux would be flowing downward from the positive central pole of the magnet through the soft iron 9^a inside the coil 16, into the polar face 12^b of the rotor, thence through the rotor shaft and the annular poles 1^b, 1^c, to the negative poles of the magnets. As the reluctance of the path 4^c, 9^a, 9^b, 12^b, 12, 1^b, 1^c, 4^b, is at this time a minimum, we have the maximum flux linking the coil 16, any magnetic leakage across the air gap between the rotor 12 and the polar faces 9^c being at this time substantially negligible.

As the flux distributor revolves counter-clockwise, the reluctance of the path at 9^c, 12^b, 12 increases and the reluctance of the path at 9^c, 12^b, 12 decreases. As a result more of the flux from 4^c goes around to 4^b by way of the polar faces 9^c, and less flux passes through the coil 16.

At this point when the flux through the coil 16 begins to decrease, the movable electrode 38 of the circuit opening and closing mechanism engages with the electrode 39, thus short circuiting the primary winding 16^a on itself, and the decreasing flux induces a current in this primary winding which opposes the further decreasing of the flux therethrough. In other words, a current is induced which tends to drive a magnetic flux through the coil, in the direction 100 and having a tendency to magnetize the permanent magnet.

As the flux distributor 12 turns farther around, the flux change operating inductively on the coil 16 becomes very rapid 105 and the current induced in the short circuited primary winding 16^a, comparatively large. At this point the cam 45 operates to move the electrode 38 away from the electrode 39, thereby opening the primary circuit. For an instant the condenser 23 absorbs the current previously flowing through the breaker electrode, thus giving these breaker electrodes time to get separated an appreciable distance before the potential 115 rises, so as to effect a sparkless break which insures a very quick interruption of the primary current.

The energy stored in the condenser meanwhile may dissipate itself as I^2R loss in the winding 16^a, through which an oscillatory discharge flows from the condenser. The self induction of the coils and the capacity of the condenser are of such value that the condenser current never becomes sufficiently 125 large to have an appreciable demagnetizing action upon the permanent magnets.

The sudden interruption of the current

- due to the opening of the breaker mechanism accelerates the flux decrease in the coil surrounding the polar projection 9^a, and an exceedingly high voltage is generated between the terminals of the spark gap 52. When this voltage rises to a magnitude sufficient to break down the dielectric in the spark gap an electric discharge between the electrodes of the spark gap follows.
- 10 The current generated, as above stated, always flows in such direction as to produce a magneto motive force tending to magnetize the permanent magnet.

By the time the electric discharge occurs between the electrodes of the spark gap, most of the magnetic flux is flowing from the polar face 4^c through the soft iron 9^b, 9^c polar faces 9^a, rotor 12, annular pole pieces 1^b, 1^c, to the polar faces 4^b, only a negligible amount of flux threading the coil 16 and leaking across the air gap between the polar face 9^c and the rotor 12.

As the rotor leaves the horizontal position, the flux begins to increase through the coil 16 due to the decreasing reluctance of the circuit 4^c, 9^a, 9^c, 12^b, 12, 1^b, 1^c, 4^b, the reluctance of the circuit 4^c, 9^b, 9^a, 12, 4^b, increasing, simultaneously. At this time the breaker electrodes 38, 39, are separated, that is, the primary circuit 16^a is open, so that no current can flow in the coil 16^a.

When the rotor again reaches a vertical position the flux is again a maximum in the coil and the cycle is repeated.

35 By providing the pole piece 1^d opposite the polar projection 9^a, the rotor is magnetically balanced, that is, the magnetic pull on it from above and below is approximately equalized so that the load upon the bearings 40 13 is made more uniform. However, such use of the pole piece 1^d is not at all essential, as is indicated in Fig. 20 which shows a construction without such pole piece.

It should be noted, in connection with the 45 operation above described, that the current in the coil never flows in such a manner as to demagnetize the magnet, its tendency being always to magnetize; there is always a unidirectional flow in the rotor of the major 50 part of the magnetic flux and, in case the pole piece 1^d is omitted, of all such flux, so that the rotor is really only a flux distributor, and eddy current and hysteretic losses in it are very small; the permanent 55 magnet always has a magnetic path of low reluctance for the flux between its poles, thereby much improving the keeping qualities of the permanent magnet; and the soft iron polar projections 9^a, and 9^b, 9^c, are always excited to the same polarity by the 60 permanent magnet, hence the leakage between them is negligible.

The parts of the rotor which rotate with in the annular poles need not be laminated

for the reason that substantially no currents 65 will be generated in the rotor mass owing to the uniform density of the magnetic field surrounding it. The central part of the rotor rotates always in a magnetic field of a certain polarity and the tips of the rotor 70 only may be the seats of induced current.

It will be further noted that the paths of least magnetic reluctance established by the flux distributor always extend from the extreme polar end faces of the magnet, in 75 other words, such paths of reluctance are not alternately shifted up and down over a considerable portion of the body of the polar end of the magnet structure, as is the case in many existing types of magneto genera- 80 tors, for example, ordinary horse shoe types.

In assembling the structure illustrated in the drawings, the flux distributing section 12^a is inserted between the annular pole pieces 1^b, 1^c and then the shaft of the rotor 85 is introduced through one annular pole piece, and then through the flux distributing section and forced into proper working relation with said flux distributing section, preferably under pressure.

If desired the magnet lamineæ may be formed as illustrated in Fig. 12 and Fig. 13, or any other suitable magnet structure 90 may be employed.

The operation of the automatic spark advance mechanism is most simple. When the rotor is at rest each spring 86 acts upon the adjacent centrifugal arm with which it engages in such manner as to hold the gear segment on said arm 84 in such position that 100 the flux distributing section 12^a of the rotor 12 bears a certain angular relation to the clutch element 83. This relationship is such as to effect a late or retarded spark in the cylinder of a motor, the crank shaft 105 of which we will assume is geared to the clutch 83. When the casing 82, through the instrumentality of the clutch 83 is rotated, the arms 84 are subjected to the action 110 of centrifugal force. Consequently as the speed of rotation of the casing 82 is increased the centrifugal action of the arms 84, which are suitably proportioned to the mass of the inductor rotor, will effect angular advance rotation of the rotor 12, so as 115 to cause an earlier opening of the circuit by the breaker 32, all the while maintaining substantially a constant relative position of the flux distributing section 12^a to the polar faces 9^c and 9^a, 9^b, at the instant of operation 120 of the circuit opening and closing means to open the circuit. Having angularly, so to speak, advanced the rotor, should the speed of the casing 82 then be lessened, the springs 86, compressed under the outward 125 movement of the arms 84 due to centrifugal action, now act to press the free ends of the arms inwardly toward the axis of the

rotor 12, thereby angularly retarding the action of the breaker and simultaneously angularly retarding the flux distributing section 12^a in relation to the casing 82.

5 By a slight modification of the construction hereinbefore specifically described, a generator of my invention may be readily adapted for use on either a three or a six cylinder motor and geared to run at crank 10 shaft speed thereon. This modification consists in forming the flux distributing section 12^a with three polar surfaces instead of two and with three high points on the cam for the breaker, instead of two, as in the 15 specific construction hereinbefore described, and suitably shaping and disposing the polar faces 1^a, 9^a, 9^b, and 9^c relatively thereto. These polar surfaces of the modified flux distributor for three and six cylinder ignition, as illustrated in Figs. 20, 22 and 23, are disposed with their axes 120 degrees from each other, as are also the high points 20 of the cam. It will be noted, that with this construction of flux distributor two impulses 25 or waves of electro-motive force will be generated at each 120 degrees of rotation of the rotor, one wave being due to increasing flux density and the other to decreasing flux density. In other words, for each rotation 30 of the rotor there will be available for current generation three waves due to decreasing flux density. By this arrangement excessively high speeds of rotation of the rotor incident to the one and one-half gear ratio 35 between armature shaft and crank shaft of the motor which has heretofore been used for six cylinder ignition, is avoided, and in addition a suitable speed of rotor for three cylinder ignition is secured.

40 Whereas I have hereinbefore specifically described a construction whereby it is possible to effect relative angular adjustment of the rotor to the magnet and field structure, it will be understood that substantially the 45 same result may be obtained by providing for angular adjustment of the pole structure carrying the generating windings relative to the rotor. An example of this last referred to construction is illustrated in Figs. 50 21, 22 and 23, wherein parts like those hereinbefore described are similarly numbered and wherein 9^a is a polepiece having its upper surface in magnetic contact with the polar faces 4^a of the magnet, this relationship 55 being maintained in any suitable manner, as by screws 89, extending through said pole piece and into the center rib 5. The under polar face 90 of the pole piece 9^a is curvilinear in shape, being formed in the arc of 60 a circle struck from the axis of the rotor 12 as a center. In this construction the laminated pole structure 9 is, as an entirety, angularly adjustable about the axis of the rotor 12 and relative to the polar face 90. 65 The upper polar surface 9^a of the pole struc-

ture 9 is also formed in the arc of a circle struck from the axis of the rotor shaft as a center, so that it is concentric with the arc of the polar surface 90, and these two curved surfaces are disposed relatively to each other 70 as closely as commercial standards of manufacture will permit and allow relative movement of these parts.

The side plates 9^c in this modified construction are made of suitable non-magnetic material, such as manganese bronze, and are extended downwardly, and each is provided with an annular boss or flange 9^c. The side plate 9^c at the driving end of the generator is loosely mounted on an annular projection 80 1^a of the annular polepiece 1^b, while the other side plate 9^c is mounted upon and rigidly secured to the inner end of a breaker casing 91, which casing comprises the annular sections 91^a and 91^b mounted within 85 the annular polepiece 1^c to turn loosely therewithin, and the rear extension or breaker box 91^b.

92 is a screw for securing the adjacent side plate 9^c to the section 91^a. The anti-friction bearing 13 for the rear end of the 90 rotor shaft is mounted in the section 91^b.

91^a is an end or cover plate for the breaker casing. It may be secured thereto by screws, not shown, or in any suitable manner. It 95 carries an inwardly extending flange 91^c, the inner end of which engages with the outer race of the adjacent bearing 13 so as to properly position the latter. In this construction the breaker cam 45 is arranged at 100 the rear end of the rotor shaft and rigidly secured thereto by means of screws 93 and washer 94. The breaker arm 33 is provided with an insulating bushing 33' of suitable material, such as hard fiber, and this bushing 105 is pivotally mounted upon a stationary stud 34 carried by the breaker casing. The breaker spring 37 is connected at 37^a to the breaker arm, and its opposite end is rigidly secured at 37^b to a binding post 37^b, carried 110 by the breaker casing 91 and suitably insulated therefrom, as by an insulating block 37^c, carried by the breaker casing. At one end the breaker arm 33 carries a movable electrode 38 arranged to make electrical contact with an electrically grounded stationary and adjustable electrode 39. The other end of the breaker arm carries a fiber block 115 or shoe 44, which engages with the surface of breaker cam 45.

91^b is a cap or plate pivotally mounted at 95 on the breaker casing to be swung at will in such manner as to facilitate inspection of the breaker terminals 38 and 39.

In this construction the conductor 50 leading from the common connection at 18 for the condenser and relatively coarse winding, is electrically connected to the binding post 37^b and thence through the spring 37 and arm 33 to the electrode 38.

91^a is a lug on the breaker casing by means of which mechanical connection may be made therewith to provide for the angular adjustment of the breaker casing and magnetic pole structure 9, which adjustment may be effected manually or automatically as desired.

It will be understood with this construction, that for the purpose of obtaining advance and retarded ignition the magnetic pole structure 9 is angularly adjusted relative to the magnet structure 4 in such manner that, when the position of the breaker cam is once set, adjustment for advance and retard spark may be obtained with assurance that the breaker will always operate at substantially the same point in each generating cycle irrespective of the angular position of advance or retard of the pole structure 9 with relation to the magnet structure 4.

Since in the embodiment of my invention illustrated in Figs. 21, 22 and 23, the generating winding 16 is movable relatively to the magnetic structure 4, condenser 23 and high tension terminal 26, suitable provision to allow for such relative movement should be made. This may be accomplished in any desired manner. Purely for the purpose of illustration I have shown coiled wires for each of the connections between the opposite ends of the coarse wire winding 16^a and the condenser, and ground, respectively, and another between the outer end of the fine wire winding 16^b and the plate 27. These coiled wires will allow of relative movement of the parts which they connect. It may suffice to ground one terminal of the winding 16^a to the adjacent side plate 9^a in this construction, instead of to the magnet structure 4.

To those skilled in the art of making apparatus of the class described, many alterations in construction and widely differing embodiments and applications of my invention will suggest themselves, without departing from the spirit and scope thereof. My disclosures and the description herein are purely illustrative, and are not intended to be in any sense limiting.

50 What I claim is:—

1. In an apparatus of the class described, the combination of a magnet and field structure having at one of the magnet poles an annular pole piece and at the opposite magnet pole a plurality of polar projections, a generating winding arranged in inductive relation to one of said polar projections and an inductor rotor extending through said annular pole piece and having a section movable relative to said polar projection to cooperate therewith in establishing paths of least magnetic reluctance first through and then outside of said generating winding.

2. In apparatus of the class described,

ture having at one magnet pole a plurality of polar projections disposed in a plane at right angles to the plane of said magnet and field structure, a generating winding arranged in inductive relation to one of said polar projections, and an inductor rotor extending axially from the plane of said polar projections to the other pole of the magnet and having a section movable relative to said polar projections and coöperating therewith to establish paths of least magnetic reluctance first through and then outside of said generating winding.

3. In an apparatus of the class described, the combination of a magnet and field structure having at one magnet pole thereof a plurality of polar projections disposed in a plane transverse to the plane of the magnet, a generating winding arranged in inductive relation to one of said polar projections, an inductor rotor disposed in the plane of said magnet and field structure and extending axially from the said polar projections to the opposite pole of the magnet so as to afford a continuous uni-directional path for flux between the magnet poles, said rotor having a section movable relative to said polar projections and coöperating therewith to establish paths of least magnetic reluctance first through and then outside of said generating winding.

4. In an apparatus of the class described, the combination of a pair of magnetic circuits arranged with two like poles in consequent pole relationship to each other and the other two poles of like polarity spaced apart, a plurality of polar projections excited to the same polarity by said consequent poles, a generating winding in inductive relation with one of said polar projections, and a flux distributor disposed in said magnetic circuits and forming at all times paths for unidirectional magnetic flux between said consequent poles and the other poles of said magnetic circuits, and having a section movable relative to said polar projections to effect variations in flux density through said generator winding.

5. In apparatus of the class described, the combination of a magnetizable base section, a pair of permanent magnets with two of their poles of like polarity arranged in consequent pole relationship to each other and their other two poles spaced apart and each in magnetic contact with said base section, a plurality of polar projections excited to the same polarity by said consequent poles, a generating winding in inductive relation with one of said polar projections, and a flux distributor mounted in said base section and serving to establish at all times paths of low magnetic reluctance between said polar projections and the poles of said magnets which are in contact with said base section.

6. In apparatus of the class described, the

- combination of a magnetizable base section, a pair of permanent magnets with two of their poles of like polarity arranged in consequent pole relationship to each other and 5 their other two poles spaced apart and each in magnetic contact with said base section, a plurality of polar projections excited to the same polarity by said consequent poles, a generating winding in inductive relation 10 with one of said polar projections, and a flux distributer mounted in said base section, serving to establish at all times paths of low magnetic reluctance between said polar projections and the poles of said magnets which 15 are in contact with said base section and movable to effect variations of magnetic flux density through said generating winding.
7. In apparatus of the class described, the combination of a magnetizable base section 20 having a pair of aligned annular pole pieces, a pair of permanent magnets with two of their poles of like polarity arranged in consequent pole relationship to each other and their other two poles spaced apart and each 25 in magnetic contact with one of said annular pole pieces of said base section, a plurality of polar projections excited to the same polarity by said consequent poles, a generating winding in inductive relation to 30 one of said polar projections, and a flux distributer extending at either end within the adjacent annular pole of said base section and having a section movable relative to said polar projections and coöperating there- 35 with to effect variations of magnetic flux density through said generating winding.
8. In apparatus of the class described, the combination of a magnet and field structure, a generating winding arranged in in- 40 ductive relation with said magnet and field structure, and a flux distributer movable relative to said field structure and coöperating therewith to establish three times during each complete revolution of said flux dis- 45 tributer paths for a unidirectional flux first through and then outside of said generating winding and unidirectionally through said flux distributer throughout the cycle of operation, whereby the flux passing through 50 said flux distributer is not reversed during said cycle.
9. In apparatus of the class described, the combination of a magnet and field structure, a generating winding arranged in inductive 55 relationship to said magnet and field structure, and a flux distributer having three distributing sections with polar faces arranged one hundred and twenty degrees from each other about the periphery of said flux dis- 60 tributer and movable relative to said field structure and coöperating therewith to es- tablish three times during each rotation of said flux distributer paths for a unidirectional flux first through and then outside of 65 said generating winding.

10. In apparatus of the class described, the combination of a magnet, a plurality of polar projections adjustably mounted relative to one of the poles of said magnet, a generating winding supported by one of 70 said polar projections, and a flux distributer movable relative to said polar projections and coöperating therewith to establish paths of least magnetic reluctance first through and then outside of said generating winding. 75

11. In apparatus of the class described, the combination of a magnet, a plurality of polar projections adjustably mounted relative to one of the poles of said magnet, a generating winding supported by one of 80 said polar projections, a flux distributer movable relative to said polar projections and coöperating therewith to establish paths of least magnetic reluctance first through and then outside of said generating winding, and 85 means for adjusting said polar projections relative to said magnet and also to said rotor.

12. In apparatus of the class described, the combination of a base, a permanent mag- 90 net thereon, an inductor rotor mounted on said base, a plurality of polar projections supported from said base and interposed be- 95 tween one of the poles of said magnet and said inductor rotor and movable relative to said magnet and said inductor rotor, and a generating winding carried by one of said polar projections.

13. In apparatus of the class described, the combination of a base, a permanent mag- 100 net thereon, an inductor rotor mounted on said base, a plurality of polar projections having supporting plates of non-magnetic material swingably supported from said base and interposed between one of the poles 105 of said magnet and said inductor rotor and movable relative to said magnet and said in- 110 ductor rotor, and a generating winding car- ried by one of said polar projections.

14. In apparatus of the class described, 110 the combination of a base, a permanent mag- net thereon, an inductor rotor mounted on said base, a plurality of polar projections supported from said base and interposed be- 115 tween one of the poles of said magnet and said inductor rotor and movable relative to said magnet and said inductor rotor, a gen- erating winding carried by one of said polar projections, and a circuit opening and clos- 120 ing mechanism for said generating winding adjustable with said polar projections and a cam carried by said rotor for operating said opening and closing mechanism.

15. In apparatus of the character de- 125 scribed, the combination of a field magnet having at one of its poles a plurality of polar projections, a generating winding on one of said polar projections the other of said polar projections being unwound, and a ro- 130 tatable flux distributer having a shaft sec-

tion extending close to the opposite pole of the magnet and a part arranged adjacent the said polar projections of the magnet, said distributor being adapted when turned to vary the flux density threading through the generating winding and to sustain constantly the flux between the poles of the magnet.

16. In apparatus of the character described, the combination of a permanent field magnet having at one of its poles a plurality of adjacent polar projections, a generating winding on one of said polar projections, the other polar projections being unwound, and a rotatable flux distributor having a shaft section extending close to the opposite pole of the magnet and a part arranged adjacent the said polar projections of the magnet, said distributor being adapted when turned to vary the flux density threading through the generating winding and to carry constantly in one direction the flux between the poles of the magnet.

17. In apparatus of the character described, the combination of a permanent field magnet, a generating winding in inductive relation with said magnet, metallic means extending from one pole of the magnet to the opposite pole thereof for carrying a continuous, unidirectional flux of the field, said means comprising a continuously rotating flux distributor for increasing and decreasing the flux threading through the generating winding, and means for opening the circuit through the generating winding while the flux threading therethrough is decreasing.

18. In apparatus of the character described, the combination of a permanent field magnet, a generating winding in inductive relation with said magnet, metallic means extending from one pole of the magnet to the opposite pole thereof for carrying a continuous, unidirectional flux of the field, said means comprising a continuously rotating flux distributor for increasing and decreasing the flux threading through the generating winding, and means for closing and opening the circuit through the generating winding while the flux threading therethrough is decreasing.

19. In apparatus of the character described, the combination of a permanent field magnet, a generating winding in inductive relation with said magnet, metallic means extending from one pole of the magnet to the opposite pole thereof for carrying a unidirectional flux of the field, said means comprising a continuously rotating flux distributor for increasing and decreasing the flux threading through the generating winding, and means for opening the circuit through the generating winding while the flux threading therethrough is decreasing.

20. In apparatus of the character described, the combination of a permanent field magnet, a generating winding in inductive relation with said magnet, metallic means extending from one pole of the magnet to the opposite pole thereof for carrying a unidirectional flux of the field, said means comprising a continuously rotating flux distributor for increasing and decreasing the flux threading through the generating winding, and means for closing and opening the circuit through the generating winding while the flux threading therethrough is decreasing.

21. In apparatus of the character described, the combination of a field magnet having an adjustably mounted polar projection through which the flux of the magnet flows always in the same direction, a generating winding on said polar projection, a rotary flux distributor for varying the density of the flux threading through the generating winding, means for opening the circuit through the generating winding at a certain point in the movement of the flux distributor, said means being adjustable to advance or retard the point at which the circuit is opened, and means for simultaneously adjusting the polar projection with its generating winding and the said circuit opening means, whereby the relative positions of the polar projection and the flux distributor at the opening of the circuit are maintained the same as the point of such opening is advanced or retarded.

22. In apparatus of the character described, the combination of a field magnet having an adjustably mounted pole piece formed with a plurality of polar projections, a generating winding on one of said projections, a rotary flux distributor for shifting the field flux alternately through the wound polar projection and an unwound polar projection, means for opening the circuit through the generating winding at a certain point in the movement of the flux distributor, said means being adjustable to advance or retard the point at which the circuit is opened, and means for simultaneously adjusting the polar projection with its generating winding and the said circuit opening means, whereby the relative positions of the polar projection and the flux distributor at the opening of the circuit are maintained the same as the point of such opening is advanced or retarded.

23. In apparatus of the character described, the combination of a permanent field magnet, pole pieces in magnetic contact with the polar faces at the ends of the magnet, a generating winding in inductive relation with the field of the magnet, a flux distributor coöperating with the pole pieces to vary the amount of flux threading through

the said winding, the flux distributer being relatively distant from those parts of the permanent magnet other than the said polar faces, and means for closing and opening the 5 circuit of the generating winding during decrease of magnetic flux density there-through effected by the operation of the flux distributer.

24. In apparatus of the character described, the combination of a magnetic field structure having a plurality of polar projections, a high tension generating winding in inductive relation to said polar projections, a continuously rotating unwound 10 flux distributer coöperating with said polar projections to maintain therewith at all times a closed magnetic circuit and to increase and decrease always in one and the same direction the flux threading through 15 said generating winding, means for opening and closing an electric circuit through said generating winding, and means for simultaneously effecting relative angular displacement of the polar faces of said flux distributer and the polar faces of said polar projections and the advancing and retarding of 20 operation of said circuit opening and closing means.

25. In apparatus of the class described,

Copies of this patent may be obtained for five cents each, by addressing the "Commissioner of Patents, Washington, D. C."

the combination of a field magnet structure 30 having a plurality of polar projections, a generating winding having a spark gap, said winding being arranged in inductive relation to said field structure, an unwound flux distributer constantly rotating relative to 35 said polar projections when in operation alternately to increase and decrease the flux linking through said winding and to maintain the path of least reluctance for the magnetic circuit always in the same electro-magnetic 40 relation to said winding, means for closing and opening an electric circuit through said winding in a definite timed relation to said distribution of flux, and means for advancing and retarding simultaneously 45 said distribution of flux and the opening and closing of said circuit whereby high tension sparks having curved waves of like shape and value for a given frequency throughout the range of spark adjustment are caused 50 periodically to jump said spark gap.

In testimony whereof I affix my signature, in the presence of two witnesses.
